UNITED STATES PATENT OFFICE

AUSTIN H. DOWNS, OF NEWARK, NEW JERSEY, ASSIGNOR TO ECLIPSE AIR BRUSH COMPANY, INC., OF NEWARK, NEW JERSEY, A CORPORATION OF NEW JERSEY

TANK AND AGITATING CONSTRUCTION FOR PAINT-SPRAYING APPARATUS

Application filed January 23, 1928. Serial No. 248,725.

This invention relates to improvements in tank and agitating mechanism therefor and is particularly adapted for apparatus of this character which is designed for and used in connection with paint spraying equipment.

The principal object of this invention is the provision of a tank or container of any size adapted to hold liquid to be sprayed or distributed under pressure and having an agitating mechanism provided within the tank, with means for driving said agitating mechanism mounted on top of the tank.

A further object of this invention is the provision of such a structure in which the agitating means is securely and properly held in position in the lower part of the tank and in which the tube or pipe through which the liquid is discharged from the tank is also suitably held in position, these parts forming a single assembly.

Further objects of this invention include improvements in details of construction and arrangement whereby an efficient construction of this kind is provided capable of commercial production and assembly on an economical basis and also designed for and capable of performing the work required.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which shows, merely for the purpose of illustrative disclosure, a preferred embodiment of my invention, it being expressly understood, however, that various changes may be made in practice within the scope of the claims without digressing from my inventive idea.

In the drawings—

Figure 1 represents what we may call a front elevation of a tank or container constructed in accordance with this invention.

Figure 2 is a top plan view thereof.

Figure 3 is a view taken for the main part in vertical cross section on line 3—3 of Figure 1.

Figure 4 is a perspective view of the lid

or cover for the tank or container and the attached parts, which are positioned within the tank or container, including the agitating means and means for holding the same in position, and the discharge tube or pipe associated therewith.

Referring now to the drawings, the numeral 1 designates the body of the tank or container. This may be of almost any size and shape commensurate with the requirements of the work and is preferably of metallic construction and of sufficient strength to withstand considerable fluid or air pressure which is applied thereto in practice for the purpose of forcing the liquid therefrom to the paint spraying or other apparatus.

The lid or cover is designated generally by the reference character 2. This is also metallic and of a shape corresponding to the shape of the upper open end of the tank or container. It is provided with the groove or recess 3 to form a seat for the packing 4 and also has the laterally extending ears 5 adapted to receive the clamping wing nut and bolt construction 6, which is pivotally mounted as at 7 on the tank or container. This lid or cover may also be provided with handles 8 for the purpose of lifting and ready removal.

This lid or cover is arranged to support the agitating means, the fluid discharge pipe, means for driving the agitating means and various pipe connections with their attached parts, whereby air or other fluid pressure may be supplied to the tank or container and to the instrument for applying the liquid, such as a paint spray gun, as well as an air filter, gauges and valves of various kinds. The top of the lid or cover is provided with a plurality of upwardly extending studs 9 which are adapted to support the plate 10 in a position raised and spaced above the top surface of the lid or cover. On this plate or support 10 is mounted a motor 11, which in the form shown is an electric motor and has the driving bevel gear 12 secured to the end of the drive shaft 13. Another and larger stud or boss 14 extends upwardly from another part of the lid or cover 2 and receives at its upper end a bearing 15 which rotatably

receives the shaft 16 for operating the agitating means. This shaft 16 has the bevel gear 17 on its upper end meshing with the driving bevel gear 12, as clearly shown in Figure 3. 5 The shaft 16 extends through the lid or cover to near the bottom of the tank or container and has the packing gland construction 18 provided in the lid or cover to make the joint fluid-tight. The lower end of the shaft 16 10 has a bearing in the frame or plate member 19 and on its extremity has the agitating member 20 which is in the form of a multiple bladed propeller-like element. This frame or plate member 19 is positively and securely 15 held in spaced relation to the various parts of the tank or container from the lid or cover 2 thereof by means of a plurality of rods 21 which are securely attached at their lower ends to the frame or plate 19 and at their 20 upper ends are screwed into a substantial part 22 of the lid or cover. In the form shown this substantial part 22 is in the form of a raised, thickened portion and also acts to receive the packing gland construction 18 previously described.

This frame or plate member 19 also serves as a means for holding in proper relation to the other parts the liquid discharge pipe 23, the lower end of which fits through an opening in the plate or frame 19 and the upper end of which passes through the lid or cover 2 as at 24. At the upper end of this liquid discharge pipe 23 are the connections 25 to which the other tubes, pipes or conduits are adapted 30 to be connected to convey the liquid to the point of application, such as a paint spray gun or the like, as is well understood.

Referring more particularly to Figure 2, the numeral 26 designates an air or fluid 40 pressure pipe having a connection with a suitable source of pressure and 27 a filter thereon and 28 a continuation of this air pipe, which passes under the plate 10 on which the motor 11 is mounted. This pipe 28 has 45 one branch 29 in which is positioned a valve 30 and reducing valve 31 and a gauge 32, which leads through the lid or cover of the tank or container so as to apply suitable air or other fluid pressure to the tank or container and upon the liquid contents thereof, whereby its liquid contents will be forced 50 through the liquid discharge pipe 23 under pressure when the liquid discharge valve in the applying instrument is opened. The pipe 28 has another branch 33 in which is positioned a valve 34, a reducing valve 35 and a gauge 36, and which has the connection 37 55 adapted to receive a hose, pipes or other conduits, which in turn are adapted to be connected to the application instrument, such as a paint spray gun or the like. These parts are all suitably mounted upon and supported 60 on the lid or cover of the tank or container and, therefore, form a very conveniently arranged assembly for the control of the pres-

sure under which the apparatus is designed to operate, and to insure that the liquid in the container, such as paint, lacquer and in fact any fluid or plastic substance, adapted to be applied under pressure, will be thoroughly 70 mixed and agitated before being discharged from the liquid discharge pipe.

The assembly of the agitating means and the driving means therefor on the lid or cover results in a firm and secure construction for 75 the agitating means insuring a direct drive for the same with the consequent agitation of the liquid and the supply of an even mixture through the liquid discharge pipe to the point of application. Not only that but the fluid 80 discharge pipe is securely held with its inlet end near the agitating member and in a fixed relation thereto, with the obvious consequent advantages of even mixture of the liquid.

The parts are all easily made and readily 85 assembled so that the apparatus forms an economically manufactured assembly having the many advantages of a much more complicated apparatus, convenient for transportation or portability and efficient in operation. 90

What I claim is:—

1. In combination with a tank or container, an apparatus of the character described including a lid or cover for the tank or container, agitating means having a bearing in said lid or cover and extending a substantial distance within said tank or container, a motor for actuating said agitating means mounted upon said lid or cover, and a fluid discharge pipe associated with said 95 agitating means and having its inlet end arranged in fixed and close relation to said agitating means, and a plate member fixedly secured within said tank or container near the bottom thereof and forming a support for 100 said agitating means and said liquid discharge pipe.

2. In combination with a tank or container, an apparatus of the character described including a lid or cover for the tank or container, agitating means having a bearing in said lid or cover and extending a substantial distance within said tank or container, a motor for actuating said agitating means mounted upon said lid or cover, and a fluid discharge pipe associated with said 110 agitating means and having its inlet end arranged in fixed and close relation to said agitating means, and a plate member fixedly secured within said tank or container near the bottom thereof and forming a support for 115 said agitating means and said liquid discharge pipe, and a plurality of rods fixedly secured to said lid or cover and to said plate member for permanently holding the same 120 in position.

3. In combination with a tank or container adapted to contain liquid under pressure, a lid or cover therefor, means for attaching the lid or cover to said tank or con- 125

tainer, and agitating means supported from said lid or cover and extending to a point near the bottom of said tank or container, a support for said agitating means including a plurality of rods fixedly secured to said lid or cover and extending downwardly therefrom, and a plate member fixedly secured to said rods and having a bearing in which part of said agitating means is mounted.

4. In combination with a tank or container adapted to contain liquid under pressure, a lid or cover therefor, means for attaching the lid or cover to said tank or container, and agitating means supported from said lid or cover and extending to a point near the bottom of said tank or container, a support for said agitating means including a plurality of rods fixedly secured to said lid or cover and extending downwardly therefrom, and a plate member fixedly secured to said rods and having a bearing in which part of said agitating means is mounted, and a liquid discharge pipe connected to and extending through the lid or cover and also to said plate member and having its inlet end positioned in close relation to the agitating member proper.

5. In an apparatus of the character described including, in combination, a tank or container, a lid or cover therefor, and fastening means to attach the lid or cover to said tank or container, a motor supporting base supported in spaced relation to said lid or cover and a motor mounted thereon, a pressure pipe adapted to be connected to a source of fluid pressure extending beneath said motor supporting base and having a plurality of branches supported by said lid or cover, one of said branches leading through said lid or cover into the tank or container and the other of said branches adapted to be connected to an instrument for the application of the liquid, and an agitating mechanism secured to said lid or cover and having the agitating member thereof positioned near the bottom of said tank or container, and operative connections for driving said agitating mechanism from said motor, said operative connections being mounted on top of said lid or cover, and a liquid discharge pipe extending through said lid or cover and having its inlet end positioned near the bottom of said tank or container and near the agitating member and having its top end adapted to be connected to the instrument for applying the liquid, whereby the liquid in the tank or container will be maintained under air pressure through the connections described and will be discharged through the liquid discharge pipe and will be agitated by the agitating mechanism so as to be delivered in an even condition to the point of application.

6. In an apparatus of the character de-

scribed including, in combination, a tank or container and a lid or cover therefor, a motor supporting base positioned upon said lid or cover in spaced relation to the top surface thereof, and a motor mounted on said base, fluid pressure connections mounted upon said lid or cover adapted to be connected to a source of fluid pressure and having one branch leading through said cover into the tank or container, and another branch adapted to be connected to an instrument for the application of the liquid in the container, an agitating mechanism journaled in said lid or cover and having an agitating member positioned near the bottom of said tank or container, operative connections for driving said agitating mechanism from said motor, a liquid discharge pipe extending through said lid or cover and having its inlet end positioned near the bottom of said tank or container near said agitating member.

7. In an apparatus of the character described including in combination, a tank or container and a lid or cover therefor, a motor supporting base positioned upon said lid or cover in spaced relation to the top surface thereof, and a motor mounted on said base, fluid pressure connections mounted upon said lid or cover adapted to be connected to a source of fluid pressure and having one branch leading through said cover into the tank or container, and another branch adapted to be connected to an instrument for the application of the liquid in the container, an agitating mechanism journaled in said lid or cover and having an agitating member positioned near the bottom of said tank or container, operative connections for driving said agitating mechanism from said motor, a liquid discharge pipe extending through said lid or cover and having its inlet end positioned near the bottom of said tank or container near said agitating member, and a plate member fixedly secured in spaced relation to said lid or cover and affording a bearing for said agitating mechanism and also for said liquid discharge pipe.

8. In an apparatus of the character described including, in combination, a tank or container and a lid or cover therefor, a motor supporting base positioned upon said lid or cover in spaced relation to the top surface thereof, and a motor mounted on said base, fluid pressure connections mounted upon said lid or cover adapted to be connected to a source of fluid pressure and having one branch leading through said cover into the tank or container, and another branch adapted to be connected to an instrument for the application of the liquid in the container, an agitating mechanism journaled in said lid or cover and having an agitating member positioned near the bottom of said tank or container, operative connections for driving said agitating mechanism from said motor, a

liquid discharge pipe extending through said lid or cover and having its inlet end positioned near the bottom of said tank or container near said agitating member, and a 5 plate member affording bearings for said agitating mechanism and also said liquid discharge pipe, and a plurality of elongated rods connected to the inner surface of said lid or cover and to said plate member for 10 supporting the same.

9. In combination with a tank or container adapted to contain liquid under pressure, a lid or cover therefor, means for holding the lid or cover on said tank or container, agitating means journaled in and supported from said lid or cover and extending to a point removed from the top of said tank or container and supporting means for said agitating means, said supporting means providing a bearing for said agitating means near 15 its lower end.

10. In combination with a tank or container adapted to contain liquid under pressure, a lid or cover therefor, means for holding the lid or cover on said tank or container, agitating means journaled in and supported from said lid or cover and extending to a point removed from the top of said tank or container and supporting means for said agitating means, said supporting means being held 20 in spaced relation to said lid or cover and affording a bearing for said agitating means near the lower end thereof.

11. In paint spraying equipment, the combination of a tank or container, a lid or cover therefor and means for fastening said lid or cover to said tank or container, said lid or cover supporting the following devices, a motor, fluid pressure connections adapted to 25 be connected to a source of fluid pressure and to admit said pressure through the lid or cover into the tank or container, said connections also being adapted to be connected to an instrument for the application of the liquid in the container, agitating means journaled in the lid or cover including an elongated shaft having an agitating member at the lower end thereof, said shaft having operative connections with said motor on top of 30 said lid or cover, and a bearing member for the lower end of said shaft supported from said lid or cover.

12. In paint spraying equipment, the combination of a tank or container, a lid or cover 35 therefor, means for fastening said lid or cover to the tank or container whereby the latter may receive fluid pressure, and the following devices supported by said lid or cover, a motor, agitating means including a shaft having operative connection with said motor on top of said lid or cover, said shaft extending 40 through the lid or cover and having an agitating member on the lower end thereof, a fluid discharge pipe extending through said 45 lid or cover and adjacent to said shaft and

supporting means held in spaced relation to said lid or cover and affording a bearing for the lower end of said shaft and the lower end of said fluid discharge pipe.

In testimony that I claim the foregoing, I 70 have hereunto set my hand this 16th day of January, 1928.

AUSTIN H. DOWNS.
